Primary Examiner — Susan Bennett Hattan*Assistant Examiner* — Charles Hanson(74) *Attorney, Agent, or Firm* — Jonathan Spangler; Jennifer Russell**(57) CLAIM**

The ornamental design for an intervertebral implant, substantially as shown and described.

DESCRIPTION

FIG. 1 is a perspective view of an intervertebral implant showing our new design;

FIG. 2 is a first side view thereof;

FIG. 3 is a second side view thereof;

FIG. 4 is a first end view thereof;

FIG. 5 is a second end view thereof;

FIG. 6 is a top view thereof; and,

FIG. 7 is a bottom view thereof.

The broken line showing is included for the purpose of illustrating environment and forms no part of the claimed design.
